His ATTORNEY.

UNITED STATES PATENT OFFICE.

CHARLES N. WATSON, OF ST. JOSEPH, MISSOURI.

HAIR-WAVING INSTRUMENT.

Application filed October 16, 1925. Serial No. 62,748.

To all whom it may concern:

Be it known that I, CHARLES N. WATSON, a citizen of the United States, and a resident of St. Joseph, in the county of Buchanan and State of Missouri, have invented a certain new and useful Improvement in Hair Waving Instruments, of which the following is a specification.

My invention relates to improvements in hair waving instruments.

One of the objects of my invention is to provide a novel hair waving instrument with which waves may be made which will lie flat upon the head.

A further object of my invention is to provide an instrument with which several waves may be simultaneously made.

Still another object of my invention is to provide novel guarding means for eliminating danger of the burning of the head or fingers with the heated parts of the instrument.

A further object of my invention is to provide a novel instrument of the kind described, which is simple, cheap, durable, not liable to get out of order, which is easily and quickly operated, and which is efficient in operation.

The novel features of my invention are hereinafter fully described and claimed.

In the accompanying drawings, which illustrate the preferred embodiment of my invention,

Fig. 1 is a side elevation of my improved waving instrument, shown partly broken away.

Fig. 2 is a cross section on the line 2—2 of Fig. 1.

Fig. 3 is a central longitudinal vertical sectional view of the instrument.

Fig. 4 is a sectional view, looking upwardly, on the line 4—4 of Fig. 3.

Similar reference characters designate similar parts in the different views.

The instrument is provided with a supporting member comprising a longitudinal trough shaped sheet metal body 1, from one end of which extends downwardly obliquely a tubular extension 2 on which is fastened a handle 3, which is adapted to be gripped by the hand of the operator, who, with the same hand grasps a handle 4 on an operating lever 5, which has two arms 6, which embrace opposite sides respectively and are pivoted to the extension 2 by a transverse

pin 7. A flat spring 8 is fastened at one end to the extension 2 and extends between the arms 6 and bears against the under side of the handle 4. The tension of the spring 8 normally forces the handle 4 away from the handle 3.

The lever 5 is provided above the arms 6 with an arm 9, to which is pivoted one end of a longitudinal link 10 the other end of which is pivoted to a plate 11, which is fastened to a reciprocative sheet metal member 12, which is, preferably, arcuate in cross section, the longitudinal edges of which are respectively slidably fitted in two longitudinal grooves 13, which are formed by the longitudinal edge portions 14 of the body 1 being upwardly and inwardly turned, see Fig. 2.

The supporting member is provided with downwardly extending hollow spaced apart teeth, each of which comprises a rear metal plate 15, which is disposed transversely and at right angles to the body 1, and which has a lip 16 fastened to the under side of the body 1 by a rivet 17; and a front plate 18 having a central vertical channel portion 19, the upper end of which has a lip 20, which is fastened to the under side of the body 1 by a rivet 21. The longitudinal edges of each plate 18 are respectively folded around the adjacent longitudinal edges of the adjacent rear plate 15. Each rear plate 15 is provided at its lower end with a forwardly extending lip 22, which extends under the channel portion 19 of the front plate 18 next forward thereof.

To the under side of the member 12 are secured, as with rivets 23 a plurality of U-shaped members 24, which are disposed transversely and the arms of which form their engaging prongs 25 arranged in pairs, said pairs being disposed respectively forward of the tooth plates 18, and which extend respectively through longitudinal slots 26 in the body 1 in which the prongs 25 are movable toward and from the adjacent plates 18 with which they are adapted to co-operate to form strands of hair into waves. The prongs 25 of each pair are disposed at opposite sides respectively of the adjacent channel portion 19, and in their rearward movement are adapted to pass to the rear of the forward portion of said channel portion 19, and to press strands of hair, which may be inserted between the prongs 25.

25 and said channel portion, against said channel portion and against the remaining front side portions of the plate 18.

For heating the hair forming teeth so that 5 the strands of hair engaged thereby and by the prongs 25 may be permanently set in the wave form in which they are held by said teeth and prongs 25, any suitable heating means may be employed. In the drawings I 10 have shown as such heating means a plurality of ordinary electrical heating elements comprising respectively insulating tubes 27 disposed respectively in the channel portions 19, and respectively encircled by resistance coils 28, the terminals of which are connected in the usual manner to conductors carried in an insulating cord 29 disposed between the members 1 and 12 and through the extension 2 and handle 3. The coils 28 15 may be respectively encircled by tubes 30 of insulating material, Figs. 3 and 4, to hold them from contact with the plates 18.

To protect the hands and the head from being burned by the heated teeth and prongs 25, I provide a guard member comprising a housing 31, the top of which covers the prong carrying plate 12. The guard member 31 is open at the rear end and closed at its front end, the latter serving to protect the hands 30 and the head from the front prongs 25.

The guard member is provided with guard fingers 32 arranged in pairs at opposite sides respectively of and extending below the hair forming teeth plates 18. The lower ends of 35 the fingers 32 are wedge shaped so as to readily enter the hair, and transverse guard members 33 disposed respectively below the teeth plates 18 have their ends respectively fastened to the inner sides of the lower wedge shaped ends of the fingers 32. The members 33 serve to part the hair. Spaces 40 34 are provided between the fingers 32 and the front finger 32 and the end finger 35 of the guard member. These spaces are so disposed as to permit strands of hair to be slipped between the prongs 25 and the hair forming plates 18, when the prongs 25 are in the non-pressing position shown in Figs. 3 and 4.

50 In the operation of the instrument, the fingers 32 and 35 are disposed perpendicular to the skull, the middle fingers being shorter than the end fingers to suit the contour of the head of the person. The handle 4 and prongs 25 are disposed, as shown in Fig. 3. Strands of hair are then drawn into the spaces 34 between the prongs 25 and plates 18, after which the hand holding the handle 3 presses the handle 4 toward the handle 3, 55 thus moving the plate 12 and prongs 25 rearwardly, so that the strands of hair are respectively pressed by the prongs 25 and the front sides of the tooth plates 18, thereby being formed into waves. The handle 60 4 is held in the pressing position, for a short 65

time, to enable the heated members which engage the hair to permanently set the pressed hair in the wave like form, and in a manner such that it will lie flat on the head after the hair has been released. 70

When the handle 4 is released, the spring 8 will return the parts to the initial positions, shown in Figs. 3 and 4. The instrument is then slipped along the strands to another position and the operation, just described, is repeated. These operations are repeated until the waving of the hair has been completed. 75

The transverse guard members 33 prevent hair getting into the spaces 34 which are 80 distant from the roots of the hair, and into which the hair should not be drawn.

By having the fingers arranged so as to be perpendicular to the head, when the hair is drawn into the spaces 34, the waves formed, 85 after being released, will lie flat against the head, a disposition of them that is much desired, and which it is difficult or impossible to obtain with the usual types of wave forming instruments. 90

I do not limit my invention to the structure shown and described, as many modifications, within the scope of the appended claims, may be made without departing from the spirit of my invention. 95

What I claim is:

1. In a hair waving instrument, a supporting member having a handle and a wave forming tooth, a member having two prongs arranged to co-operate with the said tooth 100 to form hair into a wave, the pronged member being slidable on said supporting member to and from a position in which said prongs will hold the hair against said tooth, means for heating said tooth, a lever pivoted to said supporting member and adapted to be swung in one direction by a hand holding said handle, means for swinging the lever in the opposite direction, and a link pivoted to said lever and to said pronged member. 110

2. In a hair waving instrument, a supporting member having a handle and a plurality of wave forming teeth, a member having a plurality of pairs of prongs adapted to co-operate respectively with said teeth to 115 form hair into waves, the pronged member being slidable on said supporting member to and from a position in which said pairs of prongs will respectively hold strands of hair against said teeth, means for heating 120 said teeth, a lever pivoted to said supporting member and adapted to be swung in one direction by a hand holding said handle, means for swinging said lever in the opposite direction, and a link pivoted to said lever and to said pronged member. 125

3. In a hair waving instrument, a supporting member having a hair forming tooth, a member having a pair of prongs adapted to co-operate with said tooth to 130

form hair into a wave, means for moving the pronged member to and from a position in which the prongs will hold the hair against said tooth, means for heating said tooth, and a guard member mounted on said supporting member and having fingers disposed respectively at the outer sides of said tooth and said prongs and projecting below said prongs and said tooth, the space between said fingers being disposed so as to admit hair between said tooth and said prongs.

4. In a hair waving instrument, a supporting member having hair forming teeth, a member having pairs of prongs adapted to co-operate respectively with said teeth to form strands of hair into waves, means for moving the pronged member to and from a position in which the pairs of prongs will respectively hold the bunches of hair against said teeth, means for heating said teeth, and a guard member mounted on said supporting member and having pairs of fingers disposed respectively at the outer sides of and extending below said teeth and said pairs of prongs, the spaces between said fingers being disposed so as to admit hair between said teeth and said pairs of prongs.

5. In a hair waving instrument, a supporting member having hair forming teeth, a member having means for pressing hair against said teeth and movable on said supporting member to and from the pressing position, means for heating said teeth, and a guard member on said supporting member having pairs of fingers at the outer sides of and projecting below said teeth and having transverse guarding members attached at their ends to said fingers respectively below said teeth.

40 6. In a hair waving instrument, a supporting member having a hollow hair forming tooth, heating means in said tooth, a member slideable on said supporting member and having means for engaging and pressing hair against said tooth, a lever pivoted to said supporting member, and a link

pivoted to said slideable member and to said lever.

7. In a hair waving instrument, a supporting member having hair forming teeth, a member slideable on said supporting member and having pairs of prongs adapted to engage and hold strands of hair against said teeth respectively, means for heating said teeth, a lever pivoted to said supporting member, a link pivoted to said lever and to said slideable member, and a guard member mounted on said supporting member and having pairs of fingers disposed respectively at the outer sides of said teeth, said fingers having wedge shaped ends projecting respectively below said teeth, said guard member having transverse guarding members attached at their ends respectively to said wedge shaped ends below said teeth.

8. In a hair waving instrument, a supporting member having a handle and hollow hair forming teeth, a member slideable on said supporting member and having pairs of prongs adapted to engage strands of hair and hold them respectively against said teeth, means for heating said teeth, a lever pivoted to said supporting member and adapted to be swung by hand in one direction, a spring engaging said lever and said supporting member for swinging the lever in the opposite direction, a link pivoted to said slideable member and to said lever, and a guard member mounted on said supporting member and having pairs of fingers disposed respectively at the outer sides of said teeth and having wedge shaped ends projecting respectively below said teeth, said guard member having transverse guarding members attached at their ends respectively to oppositely disposed fingers below said teeth.

In testimony whereof I have signed my name to this specification.

CHARLES N. WATSON.
